(57) **CLAIM**

The ornamental design for a tyre, as shown and described.

DESCRIPTION

FIG. 1 is a front, left side perspective view of a tyre showing our new design;

FIG. 2 is a front elevation view thereof;

FIG. 3 is a left side view, the right side view being the mirror image thereof; and,

FIG. 4 is a partial enlarged front view taken from FIG. 2.

1 Claim, 4 Drawing Sheets

FIG. 1

FIG. 2

FIG. 3

FIG. 4
